UNITED STATES PATENT OFFICE.

DANIEL V. SHERBAN, OF CANTON, OHIO.

PULVERIZING MILL.

Application filed January 9, 1922. Serial No. 527,827.

To all whom it may concern:

Be it known that I, DANIEL V. SHERBAN, a citizen of the United States, residing at Canton, in the county of Stark and State of Ohio, have invented certain new and useful Improvements in Pulverizing Mills, of which the following is a specification.

My invention consists of an improvement in crushing machines or mills for the purpose of crushing or pulverizing coal or other similar material. It has for its object to provide a machine for such purpose in which the coal is delivered into a rotatable drum and subjected therein to the crushing and pulverizing action of series of loose balls operating upon the coal by gravity as the drum revolves.

The particular feature of novelty involved is in providing means for screening and carrying off the fine dust, as it is produced, from the interior of the drum, means for protecting such screen by an outer preliminary screen, and means between the inner and outer screen or shield for positively eliminating and returning to the drum any particles requiring further crushing. The machine is constructed and adapted to operate in a manner somewhat similar to that of my co-pending application Serial No. 524,524.

In the drawings,

Fig. 1 is a view in longitudinal section, showing the grinding and screening mechanism of the mill as assembled;

Fig. 2 is a cross section on the line II--II of Fig. 1.

Fig. 3 is a detail view showing a connection with a suction fan.

The main operative member of the crushing apparatus consists of a rotatable drum or tumbling barrel 2, the heads or ends 3--3 of which are mounted in suitable bearings 9--9 by means of the hollow trunnion extensions 4--4. The receiving end of the drum communicates through one of said trunnion extensions with a supply pipe or inlet conduit 5, to which lump coal is delivered from any available source with a suitable amount of air.

The other head 3 is similarly mounted by its trunnion 4 in the opposite bearing 9 and communicates through the said trunnion with a suction or exhaust fan A connected by its inlet conduit with the terminal 10 adapted to collect the dust and pulverized particles as produced, and to pass them by

a suitable delivery conduit to a furnace or other point of consumption or storage.

Centrally arranged within the drum 2 and rotatably connected with it as by flanges 60 11 is the cylindrical screen or shield 12, preferably somewhat tapered and terminating adjacent the inlet-end of the drum with intervening annular openings 13 for passage of the lump coal and air to the interior, 65 as indicated by the arrows. Within the shield 12, concentric therewith and substantially co-extensive with its operative length, is the screening cylinder 14 provided with perforations or longitudinal slots sufficiently 70 small to prevent the passage into the interior of all material except that sufficiently fine for use.

The outer screen shield 12 is similarly apertured by a series of longitudinal slots 75 15 throughout the entire area of the shield adapted to admit pulverized material, and of slightly larger size. Between the outer shield 12 and the central controlling shield or screen 14 is interposed a continuous spiral 80 conveyor 16 extending from one end to the other, and arranged to propel any particles too large for passage through screen 14 to the open end of shield 12 for return delivery to the drum 2. 85

The drum is provided with a number of crushing balls or rolling weights 17 of variously suitable sizes adapted to be carried around with the drum and to crush and grind the coal by their rolling and falling 90 action in the same manner generally as described in my application referred to. The drum is rotated by any suitable means, as a chain gear or belt drive, and is designed to be operated at the necessary speed to effect the proper annular movement to the crushing balls and enclosed mass of coal being operated upon. 95

The outer shield 12 may be conveniently made as a single casting, provided the necessary strength and protecting resistance against the impact of the balls and charge of coal, while permitting the formation of the interior spiral blades, with their accompanying supporting engagement with the inner screen in a single piece. The inner screen 14 may be conveniently made of sheet metal, wire netting, or other suitable material. 105

The construction and operation will be 110 readily understood and appreciated from the foregoing description. The machine

when supplied with coal and proper suction and accompanying air supply, and rotated at the proper speed will effect rapid and thorough crushing of the coal, with a simultaneous withdrawal and elimination by suction of the available pulverized material as produced. The separation and return of unduly large particles and their re-crushing or grinding is continuous and automatic. The machine itself is strong and durable, economical of manufacture and operation, and will maintain its efficiency during a prolonged run.

It may be made in various sizes, gauge of screening openings, or variously changed or modified by the skilled mechanic, but all such changes are to be considered as within the scope of the following claims.

What I claim is:

1. A grinding mill consisting of a rotatable drum provided with grinding balls, means for introducing material to be operated upon, a suction delivery conduit, and a compound separating screen consisting of an inner screen communicating directly with the outlet conduit and an outer surrounding screening wall.

2. A grinding mill consisting of a rotatable drum provided with grinding balls, means for introducing material to be operated upon, a suction delivery conduit, an inner screen connected with and extending inwardly from the outlet conduit, and an outer screen surrounding the inner screen and provided with clearance openings for introduction of raw material to the drum.

3. A grinding mill consisting of a rotatable drum provided with grinding balls, means for introducing material to be operated upon, a suction delivery conduit, an inner cylindrical screen connected with and extending inwardly from the outlet conduit, and an outer tapered screen surrounding the inner screen and provided with clearance openings for introduction of raw material to the drum.

4. A grinding mill consisting of a rotatable drum provided with grinding balls, means for introducing material to be operated upon, a suction delivery conduit, and

a compound separating screen consisting of an inner and an outer screening wall with an intervening spiral conveyor.

5. In combination with a rotatable drum provided with an inlet conduit at one end and a outlet conduit at the other, a concentrically arranged compound screening member communicating with the outlet conduit and extending toward the inlet conduit consisting of an outer perforated shield, an inner perforated shield, and an intervening spiral conveyor adapted to return surplus material to the interior of the drum.

6. In combination, a rotatable drum provided with endmost hollow trunnions and interior rolling grinding elements, a supply connection for introducing raw material through the trunnion to the inlet end of the drum, an air suction conduit for removing pulverized material through the trunnion from the delivery end of the drum, a centrally arranged cylindrical perforated screen communicating with the delivery trunnion and extending axially towards the inlet end, and an outer surrounding protecting perforated screen embracing said screen extending from one end of the drum to the other and having clearance openings for raw material at the inlet end.

7. In combination, a rotatable drum provided with endmost hollow trunnions and interior rolling grinding elements, a supply connection for introducing raw material through the trunnion to the inlet end of the drum, an air suction conduit for removing pulverized material through a trunnion from the delivery end of the drum, a centrally arranged cylindrical perforated screen communicating with the delivery trunnion and extending axially towards the inlet end, an outer surrounding protecting perforated screen embracing said screen extending from one end of the drum to the other and having clearance openings for raw material at the inlet end, and an intervening spiral conveyor adapted to return portions of material to the receiving end of the drum.

In testimony whereof I hereunto affix my signature.

DANIEL V. SHERBAN.
